MUSIC LEAF TURNER

Curtis W. Moss, Detroit, Mich.

Application June 8, 1945, Serial No. 593,337

4 Claims. (Cl. 84—503)

1

The leaf turner of my invention is of the kind that is to be actuated by a foot pedal from which a cable or other connecting means extend to the respective parts of the mechanism, adapted to turn sheets of music.

The purpose of my invention is to provide a light, compact device which can be easily applied to a conventional music stand.

Another object of my invention is to make my device simple in construction and economical to make, so that it can be turned out in quantity at a low cost.

I shall now describe my improvement with reference to the accompanying drawings, in which:

Fig. 1 is a perspective view of a music stand with sheets of music thereon, the view disclosing the location of my music leaf turner on said stand.

Fig. 2 is a plan view of a bracket to be affixed to the music stand and adapted to support essential parts of my turner.

Fig. 3 is a side elevation of said bracket.

Fig. 4 is a perspective view, partly exploded for better illustration, of the mechanism of my turner, with a view of a leaf holding clamp.

Fig. 5 is a perspective view, partly broken off, of the same mechanism, shown from a different angle.

Fig. 6 is the bottom view of a holder which houses the mechanism of my turner.

Fig. 7 is an enlarged side elevation of elements forming a part of the mechanism of my turner.

Fig. 8 is a top elevation of the same mechanism, the top plate of the holder being removed for a better view.

Fig. 9 is a side elevation of a leaf clamp and means to support it.

Fig. 10 is an end elevation of the clamp and supporting means shown in Fig. 9.

Similar numerals refer to similar parts throughout the several views.

The position of my turner with respect to a music stand is shown in Fig. 1 where the stand 10 supports a music sheet rack 11 and where my turning mechanism is identified by numeral 12. The mechanism is adapted to be actuated by a pedal device 14, connected with mechanism 12 by means of a cable enclosed in a sheath 13. The mechanism is contained in a holder 19, mounted on a bracket 15. Said bracket has a flat shank 16 provided with ears 16a, said shank being adapted to be fastened to a central upright member 58 of rack 11. This is done by means of cross bands 17, said member 58 being sandwiched between the shank and the bands, which are affixed to ears 16a by screws 18.

The main part of the mechanism of my leaf turner is contained in a holder 19 which includes a back wall 20 abutting the bracket 15, a horizontal top 26 and a horizontal base 26a, spaced

2

therefrom. Rotatably mounted on back wall 20 by means of a pin 22, is a segment of a crown wheel, which hereinafter shall be briefly referred to as a crown wheel. The crown wheel is provided at a point close to its outer periphery with a loop 23, the loop serving as a means of attachment to a flexible cable 24 passing downwardly through aperture 25 in base 26a. The cable, enclosed by sheath 13, extends to a pedal device 14, as mentioned above. This responds to pressure applied by foot, transmitting a downward pull on cable 24. Mounted on the above mentioned pin 22 is a spool 28. A spring 29, coiled thereon, is affixed at one end to the rim of the crown wheel 21, while the other end 30 bears against the upright surface of base 26a, to yieldingly resist the rotation of the wheel in response to the pull of cable 24. The teeth 32 of crown wheel 21 are meshed with rungs of pinion 33, the shaft 34 of which is journaled in the top 26 of holder 19. The said top is omitted from views shown in Figs. 4, 5 and 8, for clearer display of parts of the mechanism disclosed therein.

The drum-like member 35 of pinion 33 is provided with a pair of parallel arms 36, disposed radially with respect to said member. Pivottally supported by the arms by means of a pin 40, is a claw 37 extending downwardly and including at its upper end a lug 39. A coil spring 38, disposed between the body of member 35 and said lug, causes the lower end of the claw to bear inwardly towards the axis of the pinion. At the lower end, the pinion is journaled in an annular member 42 on top of a plate 41, to which said annular member is integrally connected. The plate has a outline of a cam of a spiral eccentric formation and includes a radially disposed contact face 45 for engagement with claw 37. The plate is capable of being rotated around its axis on the surface of a similar cam-like plate 51, provided with a radial contact face 52. This is best shown in Fig. 8.

A shaft 43 extends from the center of the annular member 42, downwardly through plates 41, 51 and base 26 of holder 19. The shaft is disclosed in Figs. 5, 6 and 7. At its upper end, the shaft is held securely within said annular member 42 by means of a screw 44. At its lower end the shaft supports a rod 46, which extends radially from the shaft and supports a leaf clamp 47.

The lower plate 51 includes an annular hub 53 journaled in base 26a of holder 19, as shown in Fig. 6, and supports another rod 54 carrying at its outer end another leaf clamp 47. It must be pointed out that the contact face 45 in the rotary plate 41 is somewhat more remote from the axis of the plate than the similar contact face on the lower plate 51. As a result of that, when claw 37 bears against the contact face

45 in the upper plate, it cannot reach the contact face of the lower plate. In other words, when the bearing faces of the respective plates are aligned, that is, when they are substantially one above the other, the claw will engage the face of the upper plate but not that of the lower plate. However, when the upper plate had been swung around its axis by means of said claw and the claw had been returned to its original position, said claw, inclined inwardly at its lower end by means of spring 38, will engage the contact face of the lower plate and thus will serve as a means to impart a rotary motion thereto.

As already pointed out, each rod, that is, rod 46 and 54, supports a leaf clamp 47, the latter being suspended from a conveyor 48, including rollers 49 riding on the respective rod. The conveyor and the clamp 47 are loosely connected by a member 50. The clamp, which is normally disposed in the plane of the conveyor, is capable of being turned horizontally at an angle to the plane of said conveyor.

I shall now describe the operation of my leaf turner. Assuming that a book of music is placed on rack 11 of stand 10 and is open for reading by a musician, and that one or two leaves will have to be turned in the course of said reading, a clamp on rod 46 is affixed to one leaf and another clamp on rod 54 is affixed to another leaf, next in order of pages. When it is desired to turn the first page, the pedal device 14 is depressed. This effects a pull on cable 24, actuating the crown wheel 21 against the tension of spring 29. The pinion 33 driven by the crown wheel is made to turn around its axis, whereby the claw mounted from arms on member 35 of said pinion engages the contact face of the upper cam plate, causing it to swing around its axis to about 180 degrees from its original position. As shaft 42 extending downwardly through base 26a of holder 19, rotates with said upper plate and as clamp 47, affixed to a leaf in the music book, is carried by a rod extending radially from said shaft, the rotation of the plate serves to turn over said leaf. This time the next leaf may be similarly turned by again depressing the pedal device 14. Each time when the claw has swung around the respective plate, it is made to return automatically by said coil spring 29, acting upon crown wheel 21 and by means thereof upon pinion 33.

If the operation of turning of said leaf is to be repeated, the leaves with clamps attached to them may be turned back manually to their original position.

It will be seen that the turner does not have to be limited to two leaves, but that it may be made to include three or larger number of superimposed plates each having a contact face for a claw, but each of said faces being in succession from top down a little closer to the axis of the pinion so that the claw will successively engage the respective faces one by one from top down, thus causing the rotation of rods controlling the respective leaves of a music book.

It will be understood that some changes may be made in the construction of my leaf turner without deviating from the inventive principle disclosed herein.

What I, therefore, wish to claim is as follows:

1. A leaf turner of the kind described, comprising, a plurality of rotary, cam-shaped plates,

aligned axially, each having a radial contact face but each succeeding face, from top down, being closer to the common axis of rotation than the preceding face, each plate being connected to a radially disposed rod supporting at its end a clamp for attachment to a leaf of a music book, a rotary member axially aligned above said plates but remaining in a fixed relation longitudinally to said axis of rotation, a downwardly extending claw pivotally mounted in said member, said claw being adapted to engage the contact face of each of the plates, successively from top down, and gear means responsive to a pull of a cable to apply said claw to the respective contact face to swing the respective plate around its axis.

2. A leaf turner of the kind described, comprising a plurality of cam-like plates disposed parallel to each other and adapted to rotate individually around a common axis, each plate having a radially disposed contact face, but each succeeding face from top down being closer to said common axis than the face of the plate above, an axially disposed pinion above the uppermost plate, an arm extending radially from the base 25 of the pinion, a downwardly extending claw pivotally mounted in said arm, spring means urging the lower end of the claw inwardly into engagement with the face of the respective plate, successively from top down, to turn the respective plate around its axis to the extent approximating 180 degrees, a rod affixed to each plate and extending therefrom in a plane spaced therefrom, a leaf clamp pivotally suspended from the outer end of each rod, gear means to impart a 30 rotary motion to the pinion and pull cable means to actuate said gear means.

3. A leaf turning device of the kind described comprising a plurality of horizontally disposed cam-like plates adapted to rotate around a common axis, each plate having on the marginal portion thereof a radially disposed contact face but each succeeding face, from top down, being closer to the common axis of rotation than the face above, a claw pivotally mounted above the 45 top plate for rotation around said axis, spring means causing the claw to bear inwardly from its pivoted connection towards said axis to engage successively each of the radial faces to rotate the respective plate, a rod affixed to each plate 50 and extending radially therefrom, means on each rod to be affixed to a music leaf, means to impart a rotary motion to said claw in one direction, and spring means to return the claw back to its initial position.

55 4. A music leaf turner including a casing, a vertical shaft journaled therein, a rotary member mounted on the upper end of the shaft, a claw pivoted in said member and extending downwardly thereof, spring means urging the claw 60 towards the shaft, a plurality of cam-like plates mounted thereon for rotation around said shaft, each of the plates having on its outer margin means for engagement with said claw, said means being progressively closer to the shaft, with each 65 plate following the top plate, downwardly cable means to cause the claw to rotate each plate in succession, spring means to return the claw to its initial position upon rotation of each plate and a rod extending from each plate radially, for connection with an individual music leaf.
